CLAIM

The ornamental design for a motorcycle battery connector, as shown and described.

DESCRIPTION

FIG. 1 is a top, left, front perspective view of a motorcycle battery connector showing our new design; and, FIG. 2 is a top plan view thereof.

The Dash-Dash broken line showing in FIGS. 1-2 is for the purpose of illustrating portions of the motorcycle battery connector and forms no part of the claimed design. The Dot-Dash broken line defines the bounds of the claimed design and form no part thereof.
